Patented Oct. 15, 1918.

UNITED STATES PATENT OFFICE.

AGNAR JOHNSON, OF ALBERT LEA, MINNESOTA.

MECHANICAL TOY.

1,281,384.

Specification of Letters Patent. Patented Oct. 15, 1918.

Application filed June 24, 1918. Serial No. 241,674.

To all whom it may concern:

Be it known that I, AGNAR JOHNSON, a subject of the King of Sweden, residing at Albert Lea, in the county of Freeborn and State of Minnesota, have invented certain new and useful Improvements in Mechanical Toys, of which the following is a specification.

This invention relates to improvements in mechanical toys. One object is to provide a mechanical toy adapted to be moved back and forth over a surface to cause objects carried by the toy to move in a life-like manner. A further object is to provide a toy of this type that will be simple in construction, durable, and amusing to the younger members of society. With the foregoing and other objects in view the invention consists in the combination and arrangement of parts to be hereinafter fully described, pointed out in the appended claims and illustrated in the accompanying drawing which forms a part of this specification and in which—

25 Figure 1 is a view of my toy in side elevation, two positions of the movable parts of the toy being shown.

Fig. 2 is a top plan view of the toy.

Like reference characters denote corresponding parts in both views.

The body portion of my toy comprises a bar 1 provided at one end with the handle 2, the opposite end 3 being thickened slightly, said bar being formed between its ends with the enlarged portion 4 wherein the elongated slot 5 is formed. A disk or wheel 6 is mounted at the thickened end of the bar 1 and a pitman 7 connects said wheel to an object 8, the object in this case representing a running horse, said object 8 being pivotally arranged upon a pintle 9 which extends transversely through the bar 1. Another object 10, representing another horse, is also mounted pivotally upon the said pintle 9 upon the opposite side of bar 1 with relation to the horse 8. A third object 11, in this case representing a jockey, extends through the slot 5 of bar 1 and is pivotally mounted upon a pin 12 extending through said slot, 50 the arms 13, 13^a of part 11 being disposed

above the bar 1 and the legs 14 being disposed below that bar. The legs 14 are fixed with relation to the body portion of the object and one leg is connected by pitman 15 to the pitman 7. The arm 13 is fixed with relation to the body portion of the object 11 and is connected by pitman 16 to the horse 10. The arm 13^a is pivotally connected to the body portion 11, said arm being connected by pitman 17 to the horse 8, said arm 13^a carrying the whip 18.

As the wheel or disk 6 is rotated by movement back and forth over a surface the pitman 7 will impart a rocking motion in a rotary direction to the horse 8, the pitman 15 will impart a similar movement to the object 11 which object, through the medium of its arm 13 and pitman 16 will impart a similar motion to the horse 10. The pitman 17 will transmit a rocking or "striking" motion to the whip-arm 13^a giving the jockey or object 11 the appearance of striking the horses with the whip 18. Movement is so transmitted to the horses that they rock synchronously but in opposite directions. 75 The general impression conveyed by moving the toy back and forth over a surface is that of the horses galloping and the jockey striking at them with his whip and so urging them on.

What is claimed is:

1. In a mechanical toy, a body bar having a handle at one end, a disk mounted at the opposite end of said bar, two objects pivotally connected to said bar upon opposite sides of the same, a pitman connecting one of said objects and said disk, a third object pivotally carried by said bar, a second pitman connecting the first named pitman and said third object, and a pitman connecting said third object and one of the first named objects.

2. In a mechanical toy, a body bar having a handle at one end, a disk mounted at the opposite end of said bar, two objects mounted upon a common pivot upon opposite sides of said bar, a pitman connecting one of said objects and said disk, a third object pivotally carried by said bar, a limb pivotally connected to said object, a pitman connecting 100

said limb and one of the first named objects,
a pitman connecting said third object and
the other of the first named objects, and a
pitman connecting the first named pitman
5 and said third object at its end remote from
the said pivotally supported limb.

In testimony that I claim the foregoing

as my own I have hereto affixed my signature
in the presence of two subscribing wit-
nesses.

AGNAR JOHNSON.
